FIG. 1 is a front elevational view of a pair of spectacles
embodying my new design;
 FIG. 2 is a plan view of the spectacles with a temple
broken away for convenience of illustration;
 FIG. 3 is an elevational view of one side of the specta-
cles, the opposite side thereof being of substantially the
same appearance; and
 FIG. 4 is a rear elevational view with the temples re-
moved for clarity of illustration.
